UNITED STATES PATENT OFFICE.

ALBERT VICKERS, OF WESTMINSTER, ENGLAND, ASSIGNOR TO VICKERS SONS & MAXIM, LIMITED, OF WESTMINSTER, LONDON COUNTY, ENGLAND.

FEEDING MECHANISM FOR AUTOMATIC GUNS.

SPECIFICATION forming part of Letters Patent No. 703,859, dated July 1, 1902.

Application filed November 1, 1901. Serial No. 80,818. (No model.)

To all whom it may concern:

Be it known that I, ALBERT VICKERS, steel-manufacturer, a subject of the King of Great Britain, residing at 32 Victoria street, Westminster, London, England, have invented certain new and useful Improvements in Feeding Mechanism for Automatic Guns, of which the following is a specification.

This invention relates to automatic guns, and has for its chief object to improve the construction of the feed-block, so that all the parts thereof can be detached or assembled by means of the user's fingers unaided by a tool.

15 In order that my invention may be fully understood and carried into practice, I will describe the same with reference to the accompanying drawings, in which—

Figure 1 is a side elevation of the feed-block 20 detached from the gun. Fig. 2 is a plan of the same, and Fig. 3 is a longitudinal section taken on the line 1 1 of Fig. 2. Fig. 4 is a local horizontal section on the line 2 2 of Fig. 1. Fig. 5 is an under side view of the 25 slide carrying the feed-pawls. Fig. 6 is a transverse section on the line 3 3 of Fig. 2. Fig. 7 is an under side view of a portion of the feed-block.

A is the body portion of the feed-block, 30 and B the slide carrying the feed-pawls. C D D are the retaining-pawls, and E E' are the levers, for actuating the said slide. According to my invention the said levers E E' for operating the slide B are both made in one 35 piece with their stem or spindle e instead of one of them being made separately therefrom and connected to the spindle, as heretofore. The bearing a for said spindle e is partly cut away to permit of the spindle being laterally 40 placed into position therein, and the gap formed by partly cutting away said bearing, as aforesaid, is closed by a movable piece or bearing-slide a', suitably formed to complete the bearing when in position in the block. 45 This bearing-slide is retained in proper position by the adjacent side plate of the gun when said block is inserted into place in the gun. In order to prevent the said bearing-slide from becoming unintentionally dis- 50 placed or detached when the feed-block is not in the gun or when the other parts of the

block are being assembled, I may provide a spring blade or finger a², one end of which is adapted to detachably fit into a suitably-formed recess a³ in the block and the other 55 or free end of which is adapted to lie upon or engage with a recess in the said bearing-slide. The free end of the upper lever E'—that is to say, the one that engages with the feed-block slide—is forked or similarly formed 60 to enable it to readily engage with the pin or projection b on said feed-block slide during the assembling operation.

The springs c for the feed-pawls are made in one piece, their ends remote from the pawls 65 forming part of a transverse piece c', that is adapted to fit into a suitably-formed groove or recess b', provided for its reception in the slide B. The said springs are prevented from becoming unintentionally detached by forming on the upper surface of each of the said pawls at a point immediately in advance of the free ends of the springs a notch or shoulder c². 70

The lower or retaining pawls D of the feed-block are mounted upon a removable axis-pin d, which is longitudinally split or divided at the end d', that is inserted through the block. This split end is so shaped that the members thereof tend by their resiliency to 80 expand beyond the diameter of the pin, but do not prevent the pin from being passed through the block and the feed-pawls. When, however, the pin is in place, its split end extends beyond the block (see Figs. 2 and 6) 85 and by expanding offers sufficient resistance to prevent the unintentional displacement thereof without the use of a linchpin or other locking means. The opposite end of the said axis-pin is furnished with a head or finger-piece d² for enabling it to be firmly grasped with the fingers when the pin is to be withdrawn, the said split end becoming closed by the pull exerted on the axis-pin as it is being withdrawn through the block. The springs 90 d³ for the said pawls D are made in one piece and are maintained in place by the said axis-pin d. (See Figs. 6 and 7.)

The ears F, with which the feed-block is provided for guiding the feed-belt into the 100 mouth of the block, are made smaller than heretofore and are also situated farther back

relatively to the mouth, so that they occupy a position quite close to the side plate of the gun, and consequently do not protrude so far from the face of the side plate as heretofore.

5 What I claim, and desire to secure by Letters Patent of the United States, is—

1. In a feed-block, the combination with the body portion, the slide carrying the feed-pawls, and the retaining-pawls; of slide-actuating levers formed in one piece with their stem and of a gapped bearing for said stem, substantially as herein shown and described.

2. In a feed-block, the combination with the body portion, the slide carrying the feed-pawls, and the retaining-pawls; of slide-actuating levers formed in one piece with their stem, of a gapped bearing for said stem and of a sliding piece for closing the gap in the bearing substantially as described.

20 3. In a feed-block, the combination with the body portion, the slide carrying the feed-pawls, and the retaining-pawls; of slide-actuating levers formed in one piece with their stem, of a gapped bearing for said stem, of a 25 sliding piece for closing the gap in the bearing and of means for retaining said sliding piece in place substantially as described.

4. In a feed-block, the combination with the body portion, the slide carrying the feed-pawls, and the retaining-pawls; of slide-actuating levers formed in one piece with their stem, of a gapped bearing for said stem, of a sliding piece for closing the gap in the bearing and of a detachable flexible finger for retaining said sliding piece in place substantially as described. 30

5. In a feed-block, the combination with the body portion, the slide carrying the feed-pawls, the slide-actuating levers, and the retaining-pawls; of detachable springs for the feed-pawls, comprising flexible members adapted to bear on the pawls and a transverse piece connecting the said flexible members and adapted to fit into a groove in the slide and to be maintained in such position 45 by bearing-surfaces on the pawls substantially as described.

In testimony whereof I have hereunto set my hand, in presence of two subscribing witnesses, this 21st day of October, 1901.

ALBERT VICKERS.
